UNITED STATES PATENT OFFICE.

ANNA K. MAY, OF PHILADELPHIA, PENNSYLVANIA, ASSIGNOR TO WILLIAM H. McCALLUM AND IRVING McCALLUM, OF SAME PLACE.

DESIGN FOR CARPET.

SPECIFICATION forming part of Design No. 28,826, dated June 7, 1898.

Application filed May 3, 1898. Serial No. 679,641. Term of patent 3½ years.

To all whom it may concern:

Be it known that I, ANNA K. MAY, a citizen of the United States, residing at the city of Philadelphia, in the county of Philadelphia and State of Pennsylvania, have invented and produced a new and original Design for a Carpet or other Fabric, of which the following is a specification, reference being had more particularly to the accompanying drawing, illustrating the same and forming part thereof.

The leading feature of my design is a chintz pattern of sprays of flower forms running over a suitable ground.

In the drawing, a is the body, b the border, and a b the complete carpet. c are sprays of flower forms, and d is the ground.

What I claim as my invention, and desire to secure by Letters Patent, is—

1. In a design for a carpet, the body a, substantially as shown.
  2. In a design for a carpet, the border b, substantially as shown.
  3. The design for a carpet consisting of the body a, and border b, substantially as shown. 25
- In testimony whereof I have hereunto signed my name.

ANNA K. MAY.

In presence of—

HARRY O. SWEARER,
CHAS. J. SCHAEFER.
